UNITED STATES PATENT OFFICE.

WILLIAM E. ANDRÉE, OF CHICAGO, ILLINOIS, ASSIGNOR TO THE AMERICAN LAUNDRY MACHINERY COMPANY, OF CINCINNATI, OHIO, A CORPORATION OF OHIO.

GARMENT-PRESS.

1,311,151.

Specification of Letters Patent. Patented July 29, 1919.

Application filed June 19, 1916. Serial No. 304,434.

To all whom it may concern:

Be it known that I, WILLIAM E. ANDRÉE, citizen of the United States, residing at Chicago, in the county of Cook and State of Illinois, have invented certain new and useful Improvements in Garment-Presses, of which the following is a specification.

This invention relates to garment presses employing coöperating relatively movable 10 pressing members or bucks between which the garment is pressed.

The object of the invention is to provide an improved garment press of this kind provided with means for projecting or discharging a supply of steam across the space 15 between the bucks when open and parallel with the buck face for moistening the garment or, after the application of mechanical pressure, for raising the nap. Further objects of the invention are to provide a simple and efficient construction for this purpose which is under the immediate control of the operator at all times, which enables him when the press is open, to discharge steam 20 upon the garment whenever desired, and which prevents blowing the steam in the face of the operator and quickly and evenly distributes the steam over the garment without waste.

Further objects of the invention are in part obvious and in part will appear more in detail hereinafter.

In the drawings, which represent two embodiments of the invention, Figure 1 is an end elevation of the upper portion of the machine; Fig. 2 is a plan view of the upper buck; Fig. 3 is a front elevation thereof; Fig. 4 is an end elevation, partly broken out and in section; Fig. 5 is cross section on the line 5—5 Fig. 2; Fig. 6 is a detail view of a portion of a cover or casing; Fig. 7 is a detailed sectional view, corresponding to Fig. 5, and showing a modified form of the invention; and Fig. 8 is a front elevation of 45 the buck shown in Fig. 7.

Referring to the drawings, the garment press shown, as to most of its operating parts, is of the same form and arrangement shown in my prior application for garment press, filed March 22, 1916, Serial No. 85,908, to which reference may be had for a complete understanding of the mechanism. Briefly stated the machine includes a suitable frame 1 having a support 2 for the

steam heated lower pressing member or buck 3. On an upright hollow column of said frame is pivotally mounted the supporting lever 4 for the upper pressing member or buck 5, said lever being provided with a counter-weight for said buck (not shown), 60 and being normally held in the position shown in Fig. 1 by the tension spring 6, but being capable of oscillation about its pivot to force the upper buck into pressing relation with the lower buck in the usual manner, by operation of the toggle mechanism 7, as will be readily understood. Since the present invention relates entirely to the construction of the pressing members or bucks no further description of the machine 70 is necessary.

Both the upper and lower bucks are of the usual form in so far as each comprises a hollow body portion over which is stretched a press cloth or padding 8, so that during 75 the pressing operation the garment is pressed between said press cloths. The body portions of the buck are also suitably heated, preferably by steam, and for this purpose their inner chambers are connected 80 to a suitable source of steam, the steam supply to the upper buck being through the pipe 9.

In its broadest sense the present invention contemplates the provision of suitable 85 means for projecting or discharging a supply of steam when the press is open across the face of one of the bucks, either the upper buck or the lower buck, as may be found desirable, although in the garment press shown the steam supply referred to is for the upper buck. This steam supply comes immediately from a source located at the front edge of the buck and so arranged as to discharge a cloud or 90 stream of steam in a direction parallel with the plane of the buck and across its face, from front to rear, either within or outside of the press cloth or padding.

In the form shown in Figs. 1 to 5 inclusive the steam supply is discharged within the press cloth or padding. As shown the buck along its front edge and substantially from end to end is provided with an outwardly extending flange 10, or may be 105 grooved or cut away to form a channel 11 at the lower edge of said buck. Attached to the edge of the buck along the length of

said channel, is a cover or casing 12, which may be a flat metal strip bent to angular cross section with one of its flanges attached by screws 13 to the outer face of the flange. 5 10. The other flange of said casing extends inwardly toward and terminates just short of the lower edge of the buck body, which may be slightly rounded or beveled, as shown, to form a narrow slot or passage 10 14 between the edge of the buck and the edge of the casing. This construction forms a long channel or conduit running along the front of the buck from end to end and opening through the slot 14 to the 15 face of the buck body. The padding or press cloth 8, as shown in Fig. 4, is drawn up around the outside of the cover or casing 12 and may be fastened to the buck in any ordinary manner, such as by elastic 20 straps 15 whose ends are hooked into the edge of the cloth.

The steam supply for the conduit 11 is delivered thereto by a pipe 16 opening through the flange 10 at any suitable point, 25 for example, at about the middle of the length of the buck. Below said pipe the casing or cover 12 is provided with a dam or cross wall 17, having curved side faces, as shown in Fig. 6, to deflect steam in both 30 directions toward the opposite ends of the conduit. The pipe 16 communicates at 18 with the hollow steam chamber within the buck, and in said pipe is a suitable form of quick opening valve 19 operated by 35 handle 20.

In operating the machine the garment is laid upon the lower buck and the upper buck moved down by operation of the toggle mechanism in the usual manner. Just before the press cloth of the upper buck engages the garment the valve 19 is opened to admit steam to the conduit 11, from which it is discharged through the slot 14 along the plane of the upper buck and across its 45 surface from its front to its rear edge, being quickly and evenly distributed over the garment without waste. A sufficient quantity of steam is discharged to supply moisture for the pressing operation. The lever mechanism is then operated further to force the upper buck into close pressing relation with the lower buck to apply mechanical pressure to the garment, after which it is raised, and further steam is projected across the face of 50 the buck and upon the garment to raise its nap.

The casing or cover 12 is attached to and substantially forms a part of the edge of the buck, which at all times is steam heated by 60 the supply of steam to its inner chamber. Consequently said conduit is also heated, which prevents condensation of the steam in said conduit. The construction described is also independent of automatic valves and 65 is controlled entirely by the valve 20 manip-

ulated by the operator, so that steam may be directed upon the garment whenever desired and to any required amount.

The supply of steam may also be directed across the face of the buck outside of the 70 press cloth, such an arrangement being shown in Fig. 7, and being more fully described in my copending application for garment press, executed and filed of even date herewith, Serial No. 104,435. As illustrated 75 herein the press cloth is folded up around the edge of the buck and attached thereto in any suitable manner, such as by being caught over the ends of pins 25 upon which it is held by a metal strip or guard 26 detachably secured upon the periphery of the buck. Opposite the edge of the buck and spaced slightly therefrom, is a pipe or conduit 27, whose ends may be suitably attached to the buck, as at 28 Fig. 8. This pipe communicates through a pipe 16^a with the hollow chamber of the buck, said pipe being provided with a quick opening valve of the same form shown at 19 Fig. 3. The pipe 27 is also provided with a series of closely 80 spaced small openings or the longitudinally extending slot 29, shown, through which a supply of steam may be projected across the face of the buck. To further direct said steam and prevent its free escape around 85 the edges of the lower buck, the pipe 27 may be also provided with a shield 30, just below the openings or slot 29, which may be a metal strip welded or brazed to said pipe.

In the construction just described the 100 space between the pipe and the edge of the buck enables the press cloth to be drawn around the edge of the buck without disturbing the pipe 27. It also enables any quantity of steam to be directed along the plane 105 of the buck and across its face during any stage of the pressing operation, except when the garment is under mechanical pressure, without blowing said steam into the face of the operator. The quick distribution of 110 steam also prevents waste.

What I claim is:—

1. In a garment press, a stationary buck, a movable buck supported for movement in the arc of a circle, the ironing faces of said 115 bucks being substantially radial with respect to the path of movement of the movable buck, a steaming device along the front edge only of the movable buck and adapted to project a spray of steam across the face of 120 the movable buck and toward the rear edge, and means for supplying steam to said steaming device.

2. In a garment press, a stationary buck, a movable buck supported for movement in 125 the arc of a circle, the ironing faces of said bucks being substantially radial with respect to the path of movement of the movable buck, a steaming device along the front edge only of the movable buck and adapted to 130

project a spray of steam across the face of the movable buck and toward the rear edge, means for supplying steam to the movable buck, and suitable connections for supplying steam from the movable buck to the steaming device.

3. In a garment press, a stationary buck, a movable buck cooperating therewith and provided with a channel along its edge and 10 on the underside thereof, a cover inclosing said channel and forming a conduit therewith, the edge of said cover being spaced from the edge of said movable buck to form a narrow slot opening toward the center of 15 the buck, and a steam supply pipe communicating with said conduit.

4. In a garment press, a stationary buck, a movable buck coöperating therewith and

provided with a channel along its edge and on the underside thereof, a cover inclosing 20 said channel and forming a conduit therewith, the edge of said cover being spaced from the edge of said movable buck to form a narrow slot opening toward the center of the buck, a steam supply pipe communicating 25 with said conduit, said movable buck having an inner chamber communicating with the steam supply, and a valve controlling the flow of steam from said chamber to said conduit.

In testimony whereof I affix my signature in presence of two witnesses.

WILLIAM E. ANDRÉE.
